UNITED STATES PATENT OFFICE.

MARZO ALLEN KENNEDY, OF CHICAGO, ILLINOIS, ASSIGNOR TO EDMUND A. RUSSELL, OF CHICAGO, ILLINOIS.

LOUD-SPEAKER UNIT.

Application filed March 26, 1928. Serial No. 264,938.

This invention relates to loud speaker units for radio receiving sets.

Principal objects of the invention are:

To increase the sensitiveness of loud speaker units of the general type specified;

To increase the volume and improve the quality of the sound reproduction;

To simplify the construction of the unit;

To obviate the necessity for adjustment of the reed or armature; and

To provide a loud speaker unit which will operate with substantial uniformity.

To effect the objects of the invention, a loud speaker unit embodying my invention and improvements, comprises the various features, combinations of features and details of construction hereinafter described and claimed.

In the accompanying drawings, in which my invention is fully illustrated:

Figure 1 is a sectional side view of a loud speaker embodying my invention and improvements, the section being taken substantially on the line 1—1 of Fig. 2;

Figure 2 is a bottom plan view from the position 2—2 of Fig 1;

Figure 3 is an enlarged sectional view of the loud speaker unit substantially on the line 3—3 of Fig. 1, the mounting and cone being omitted; and

Figure 4 is an isometric projection of the loud speaker unit.

Describing the invention with particular reference to the drawings, my improved loud speaker unit, designed as a whole A, comprises a base 1, which may be made of suitable non-magnetic material and which conveniently can be die cast from suitable non-magnetic metal.

Mounted on the base 1, and preferably in spaced relation thereto, is a horseshoe magnet 2, preferably a permanent magnet.

Secured to opposite poles and to opposite sides of said horseshoe magnet, are soft iron plates 3 and 4, which extend inwardly so that their unattached ends will be positioned one above the other, and secured to said plates, respectively, in axial alignment with each other are electro-magnets 5 and 6. In accordance with usual practice, the windings of said electro-magnets are connected in series and the terminals thereof are connected to binding posts 7 and 8, which as shown, are secured to a plate 9 attached to the magnet 1, as a convenient support, at a desired dis-

tance rearwardly from the electro-magnets 5 and 6, to which the conductor wires 10 for connecting the loud speaker unit with a radio or other sound receiving set are also connected. If the plate 9 is made of material which is an electrical conductor, the binding posts will be insulated therefrom in any usual or desired manner, as by fibre bushings 11.

The armature of the magnet—commonly known as the reed—consists of a plate 12 of resilient metal, preferably soft iron, the end of which remote from the electro-magnets is secured by suitable connecting means with the plate 9 and a second plate 13 secured to the opposite side of the magnet 1 from said plate 9 and directly above it. As shown, said reed or armature is connected to said plates 9 and 13 by means of clamping screws 14 which extend through holes in the plate 9 and have threaded engagement with holes in the plate 13, inserted over which are spacing sleeves 15, which are so proportioned that when the screws 14 are tightened, said reed or armature will be firmly clamped between the adjacent ends of the spacing sleeves 15, the relation being such that the free end of said reed or armature will extend between and project beyond the electro-magnets 5 and 6 and as near as may be, equi-distant from the poles thereof, being separate from both thereof by a short air gap.

Secured in the projecting end of the armature or reed 12 is a pin 16 of small diameter, mounted at the upper end of which is a cone 17, which may be made of paper, parchment or like material. The cone 17 exemplifies any suitable form of vibrator.

The pin 16 preferably is secured to the reed or armature 11 at a distance of about one-half an inch from the common axis of the cores of the electro-magnets.

Due to the manner of mounting the electro-magnets 5 and 6, one above and the other below the reed or armature 12 with their windings connected in series, it is obvious that the magnetic fields at opposite sides of said reed or armature will be of opposite potential, one repelling and the other attracting said reed or armature when said electro-magnets are energized, and that the resilience of said reed or armature will return it to normal or neutral position—wholly or partially—with variations in the strength of the current traversing said electro-magnets. A particular advantage due to the characteristic that the elec-

tro-magnets assist instead of oppose each other is that variations in the size of the gaps which separate said reed or armature from the poles of the electro-magnets, respectively, is 5 to a large extent immaterial, thus obviating the necessity for means for adjusting the position of the reed or armature relative to the poles of said electro-magnets.

Advantages inherent in my improved loud 10 speaker unit arising from the structural features described are:

1. Simplicity of construction.
2. Great sensitiveness.
3. Uniform performance.
- 15 4. Increased volume.
5. No adjustment required; and
6. Greater range of frequencies.

In use, my improved loud speaker unit may 20 be mounted for use upon any suitable support 18, which may exemplify the wall of a cabinet or other suitable support. Simple means for thus mounting the instrument consist of screws inserted through holes in the base 1 of the instrument, the lower ends of which have 25 threaded engagement with holes in the support 18, sleeves 19 preferably being inserted over said screws between the base 1 of the instrument and the support 18.

In accordance with usual practice and to 30 prevent access of dust and dirt to the loud speaker unit A, the parts thereof are preferably enclosed in a casing 20, the lower side of which is open and is adapted to be secured to the edges of the instrument base 1, being preferably fitted tightly thereto and resting upon a shoulder thereon. Formed in the top of the casing 20 is a hole 21 through which the pin 16 extends, said hole being made sufficiently 35 larger than the pin to insure that said pin 40 will not contact with the casing at the edges of said hole.

I claim:

1. In a loud speaker unit, the combination of a non-magnetic base, a horseshoe magnet

supported thereon, soft iron plates secured to 45 opposite poles and opposite sides of said horseshoe magnet the unattached ends of which overlap, electromagnets mounted on adjacent sides of the overlapping ends of said plates, the relation being such that the 50 adjacent ends of the cores of said electro-magnet will be spaced apart, the windings of said electro-magnets being connected in series, and a resilient reed secured at one end to a relatively fixed support, the relation being 55 such that the free end of said reed will extend into the space between the adjacent ends of the cores of the electro-magnets, and a vibrator connected to said reed.

2. In a loud speaker unit, the combination 60 of a non-magnetic base, a horse-shoe magnet supported thereon, soft iron plates secured to opposite poles of said horse-shoe magnet comprising overlapping portions, electro-magnets mounted on said plates with the adjacent ends 65 of the cores thereof spaced apart, and a resilient reed secured to a relatively fixed support which extends into the space between the adjacent ends of the cores of the electro-magnets, and a vibrator connected to said reed. 70

3. A loud speaker unit as specified in claim 1, in which the reed projects beyond the electro-magnets and the vibrator is connected to said reed by a pin secured in the reed.

4. A loud speaker unit as specified in 75 claim 1, in which the electro-magnets are mounted with the axes of their cores in substantial alignment.

5. A loud speaker unit as specified in claim 1, in which the gaps between the reed and the 80 adjacent ends of the cores of the electro-magnets, respectively, are normally substantially equal and constant.

In witness that I claim the foregoing as my invention, I affix my signature this 22nd day 85 of March, 1928.

MARZO A. KENNEDY.
